UNITED STATES PATENT OFFICE.

JAMES J. THOMPSON, OF CINCINNATI, OHIO.

SHEET-MUSIC TURNER.

Application filed January 3, 1922. Serial No. 526,684.

To all whom it may concern:

Be it known that JAMES J. THOMPSON, a citizen of the United States of America, residing at Cincinnati, in the county of Hamilton and State of Ohio, has invented new and useful Improvements in Sheet-Music Turners, of which the following is a specification.

The object of the invention is to provide a music leaf turner, particularly designed for use in connection with sheet music and adapted for construction independently of and suitable for application to the desk or music rack of a piano, organ, or similar keyed instrument or to an orchestral music rack, and having means for selecting and separately and independently turning the leaves of the musical composition either forward or rearward in the progress of the performance with the minimum of movement and effort upon the part of the performer or operator with the minimum of time expenditure incident to the operation thereof, to the end that the hand of the operator may be delivered to the least possible extent from the manipulation of the instrument; and with these general objects in view the invention consists in a construction and combination of parts of which a preferred embodiment is shown in the accompanying drawings, wherein:

Figure 1 is a front view partly broken away of a structure embodying the invention.

Figure 2 is a side view partly in section of the same.

Figure 3 is a horizontal section taken on a plane just below the music rest on the line 3-3 of Figure 2.

Figure 4 is a plan view of the rack.

Figure 5 is a front edge view of the slide bar which serves as the actuator for the leaf separators.

Figure 6 is an enlarged vertical sectional view on the plane indicated by the line 6-6 of Figure 2.

Figures 7 and 8 are detail horizontal sections on the planes indicated by the lines 7-7 and 8-8 of Figure 6.

Figure 9 is a detail side view of the controlling cam for the leaf arm.

Figure 10 is a detail front view of the upper portion of the binder arm and clamp for engaging the binder of the music sheet.

Figure 11 is a detail section on the plane indicated by the line 11-11 of Figure 10.

Figure 12 is a detail plan view of the actuating carriage.

Figure 13 is a transverse section taken on the plane indicated by the line 13-13 of Figure 2.

Figure 14 is a detail view of the spindle by which the operating lever is suspended.

Figure 15 is a side view partly in section showing the supplemental housing raised to permit of the closing of the keyboard cover of the instrument.

Figure 16 is a detail perspective view showing the leaf turning arm.

Figure 17 is a similar view of the slide bar.

Figure 18 is a detail perspective view of the rocking lever and its connected operating link.

Figure 19 is a detail perspective view showing one of the rockers carried by the slide bar and the fixed pin by which the rocker is actuated.

Figure 20 is a detail perspective view showing the clutch shifter.

Figure 21 is a similar view of one of the separators for co-operative action with the leaf turning arm.

Figure 22 is a top plan view of the structure of Figure 21.

The apparatus embodies a base 20 designed to be seated upon the music rack of the instrument or of the independent type employed in orchestral work and preferably made in the form of a casing for containing certain operative elements hereinafter described, so that its upper wall 21 may form the rest or support for the sheet music, with a rear flange 22 to prevent rearward displacement of the music sheet, and an upright binder bar 23, preferably hinged as indicated at 24 to the base so as to assume the inclination of the instrument rack, with a clamp 25 at its upper end to engage the instrument rack, the clamp being formed as a part of an adjustable extension 26 slidably mounted upon the body portion of the

90

binder bar and held in place by guide screws or bolts 27, said binder bar being provided with a binder clamp 28 for engaging the fold or binding of the musical composition 5 to hold it in proper position upon the rack and guard against displacement by the movement of the leaf turning elements thereof as hereinafter fully disclosed. The binder clamp in the construction illustrated 10 consists of yielding, resilient strips 29 having complementary bearing or gripping elements 30. Arranged at the upper end of the binder clamp is a transverse guide 31 and secured in engaging relation with the fold 15 or binder of a composition is a locking means 32 consisting of an element pivotally mounted as at 33 upon one of the clamp elements 29 and engaged with a pin 33' on the other element. Obviously by disengaging 20 the lock it is possible to spread or separate the elements of the binder clamp to insert the fold of the sheet music whereupon the reengagement of the lock will serve to bind the sheet in place and permit the leaves 25 thereof to be turned successively either forward or backward, as the rendition of the composition may require. To prevent forward displacement or premature folding of the leaves of the composition the pivotal 30 separators 34 may be arranged at the front edge of the rest between the center and extremities thereof, but as these elements in the construction illustrated perform other functions having a specific relation with the turning mechanism, a particular description 35 thereof will appear hereinafter.

The leaf turning arm 35 is carried by a turning head 36 mounted loosely upon the operating spindle 37 for angular or turning 40 movement with respect thereto and having a thrust bearing in the cam hereinafter described. Rotary motion is communicated to the turning head and thereby to the leaf turning arm through a lost motion connection 45 with the operating spindle which, at its upper end, is provided with a disk 38 in which is formed an arcuate slot 39 traversed by a pin 37' mounted in the turning head. The leaf turning arm, in addition to the 50 swinging movement relative to the spindle as an axis, has an oscillatory or swinging movement in a vertical plane on a horizontally disposed pivot 40 carried by the turning head eccentric to the axis of the latter. The oscillatory movement of the leaf turning arm is controlled by a cam disk 41 which is revolvably mounted upon the spindle 37 and is provided with a sleeve 42 to which is keyed a clutch member 43 capable of axial movement relative to the 55 sleeve by reason of the elongated key 44 and yieldingly held in its normal position by means of springs 45 of which the upper ends bear against a cap 46 constituting an 60 integral part of the cam disk. The cam

disk is provided with a cam rim 47 having diametrically opposite cam faces 48 for engagement with a lug 49 depending from the leaf turning arm.

When the clutch member has been actuated, so that the cam disk is simultaneously actuated upon any rotary or turning movement being imparted to the spindle 37, this movement is not immediately communicated to the turning head, because of the lost motion connection above referred to. Therefore, one of the cam faces 48 moves relatively to the lug 49 with the result that the leaf turning arm is elevated to effect engagement with a leaf about to be turned, the arm swinging on the pivot 40 as a center and assuming the position indicated in dotted lines in Figure 6. When the leaf turning arm shall have been elevated so that the bottom of the lug lies in the plane of the upper edge of the cam disk 48, the disk 38 will have turned a sufficient distance for the pin 37' to have engaged in one end of the slot 39. Thereupon, the turning head 36 is carried around with the disk 38 and the shaft 37 and rotary movement of the leaf turning arm is secured. The first or oscillatory movement of the arm engages it with the leaf and thereafter the swinging or rotary movement effects the turning of the leaf.

The spindle 37 and the clutch member 43 through which motion is communicated to the cam are adapted for actuation in opposite directions in the operation of the device, and to accomplish this operation there is provided in the construction illustrated a pair of drums 50 and 51, the latter of which is rigid with a sleeve 52 forming the hub of a clutch member 53 which is complementary to the clutch member 43 and consists in a disk having segmental keyways or peripheral cut away portions 54 and 55 adapted for respective engagement by keys 56 and 57 consisting of screws carried by the clutch member 43 which is of inverted cup form, said keys being in different transverse planes, so that the keyways of the clutch member 53 are adapted for engagement with the keys in different longitudinal adjustments relatively of the clutch members 43 and 53. For example when the clutch member 43 is in its depressed position as shown in Figure 6, in which it is yieldingly held by the springs 45, the key 57 is in the plane of the clutch member 53 and is in engagement with the keyway 55 and therefore in position to communicate rotary motion from the clutch member 53 to the clutch member 43 to turn the cam in the direction indicated by the arrow in Figure 1 to in turn cause the cam to raise the leaf turning arm 35 so that the jaws 35' thereof may engage a leaf to be turned.

Motion is communicated to the drums 50

and 51 from a traveller 58 which is mounted for horizontal sliding movement parallel with the length of the rack in a guide formed by the housing 20 and carries the 5 flexible runners 59 and 60 which have intermediate coils or bights extending around the drums 50 and 51 respectively. These runners are kept in tension by means of thumb nuts 61 and 62 and as the loops or bights 10 thereof are reversed in position relatively it will be obvious that a movement of the traveller in the direction indicated by the arrow in Figure 12 for example will impart rotary motion to the drum 50 in a direction necessary to turn the leaf arm 35 from the 15 position at the right shown in Figure 1 to a corresponding position to the left and thus will turn a leaf engaged thereby in a direction necessary to proceed with the performance 20 of the music progressively. A movement of said traveller 58 in the same direction, however, owing to the reversed position of the runner 60 will turn the drum 51 in the opposite direction, or in the direction 25 indicated by arrow on the cam in Figure 1. The drum 51 is preferably of smaller diameter than the drum 50 to cause it to have a more rapid movement than the latter with the same movement of the traveller, and by 30 reason of this differentiation of movements, together with the lost motion or pin and slot connection between the spindle and the head 36, receives a motion necessary to raise the leaf turning arm through the cam 48, into 35 engaging relation with the leaf, before the swinging or leaf turning movement of said arm is commenced.

The purpose of the two-way engagement 40 of the clutch represented by the members 43 and 53 by which motion is communicated from the drum 51 to the cam, is to permit of a corresponding movement of the parts of the mechanism in turning a music leaf backward or from the left to the right for purposes of repeating passages of the music 45 score, and as a means of adjusting the axially movable clutch member or sleeve 43 so as to bring the key 56 into engaging relation with the keyway 54, there is employed a 50 clutch shifter 63 movable upon the hub 52 in a direction parallel with the axis of the clutch and in contact with the rim of the clutch member 43, through a cam 64 consisting of a slot in a shifting rod 65 mounted for 55 forward and rearward sliding movement and forming the supporting spindle of an operating arm 66 which is provided in an exposed position close to the plane of the fingerboard of the instrument with a finger rest or grip 67 for pressure by the performer when it is necessary to turn a leaf. This 60 operating arm is loosely mounted upon the shifting rod or spindle 65 and carries a reversing arm 68 of bell-crank form yieldingly

held in its normal position by a spring 69 65 and connected by a rod 70 with a button 71 which serves as a cam to engage a disk 72 fixed to the rod 65 and communicate motion to said rod, in opposition to the pressure of a return spring 73 and in a direction necessary to cause the cam 64 to raise the clutch shifter. In other words whereas the depression of the free end of the hand lever 66 is designed by a movement of the traveller 75 58 from right to left to communicate reverse movements to the drums 50 and 51 to bring the leaf turning arm into engagement with a leaf and swing the arm from a position at the right to a position at the left and thus turn the leaf in the direction of forward 80 progress of the rendition of the composition, a corresponding movement of the hand lever by pressing upon the auxiliary lever 68 and thereby shifting the rod 65 forwardly will raise the shifter plate 63 and thereby readjust the clutch members to cause 85 a reversal of the operation and thus turn a leaf from the left to the right.

The illustrated means for communicating motion from the hand lever to the traveller 90 consists of a rocking lever 74 fulcrumed at 75 and having a pin 76 engaged with the traveller by introduction between parallel ribs 77 on the front wall of the traveller, a link 78 extending from the hand lever to the 95 lower arm of the rocking lever, and a return spring 78' being connected with said lower arm of the rocking lever to yieldingly hold the same in its normal position.

The leaf turning arm consists of parallel 100 spring elements 35^b each of which terminally carries an upturned jaw 35^a and each of which carries a depending stop lug 35^c, the lugs 35^c being arranged out of transverse alignment and being adapted for respective 105 engagement with stop pins 35^d and 35^e as the turning arm is alternately swung to the left and to the right. Assuming that the leaf turning arm is being swung from the 110 normal position shown in Figure 1 at the right to the reversed position to turn a page of the composition in the direction of progressive performance thereof, the engagement of one of the lugs 35^c with the stop pin 35^d will serve to spread the elements 115 35^b and thus separate the jaws 35^a to liberate the leaf. A reverse swinging movement of the leaf turning arm will bring the other stop lug 35^c into engagement with the stop pin 35^e and again will open the jaws to engage 120 a leaf which may be carried thereby.

In order that the engagement of the jaws 35^a with a leaf to be turned may be secured with accuracy and certainty there is employed a slide bar 79 movable by the main spindle 37 through the disk 38 which as above noted is secured to said spindle by a link 80 having terminal pivotal connection 125

respectively with the disk and slide bar, and separators 81 which are mounted upon the base or housing of the apparatus for use respectively when a leaf is to be turned from the right to the left or from the left to the right and being of corresponding construction so that a detailed description of one will suffice for both. The type of separator illustrated in the drawing embodies a rocker of bell-crank form having a spreader arm 82 and a separator arm 83, with the axis of movement represented by the spindle 84. The spreader arm 82 is tapered transversely and the jaws 35^a of the turning arm are arranged in the path of swinging movement of said arm when the operating spindle 37 first receives its movement from the operation of the hand lever 66, the connections between the slide bar 79 and the spindle 84 of the separator being such as to produce such movement, and the action of the spreader arm 82 is to pass downward between the jaws 35^a and spread the latter in position to receive the lower edge of a sheet or leaf of the composition. The slide bar 79 at each end carries a shoe 85 having a yielding adhesive contact cushion or face 86 of rubber or its equivalent adapted to be pressed against the surface of the leaf or sheet of music to be turned, the pressure of the shoe being rearward against the foremost leaf or sheet and such pressure being opposed by the rear rest flange 22 of the rack seat. As the movement of the slide bar is from right to left or in the direction indicated by the arrow in Figure 3, when for example the page is to be turned forward or in the direction of progressive performance, it is obvious that the contact of the shoe with the sheet during the said movement of the slide bar will tend to bow the sheet or leaf forwardly between the point of contact of the cushion with the sheet and the center or binding element of the composition which is held rigid by the binder clamp 28. As a separator turns therefore in the direction indicated by the arrow thereon in Figure 1 to cause the spreader arm 82 to spread the jaws 35^a of the leaf turning arm (and as the slide bar is moving to cause the shoe 85 to bow the leaf or sheet) the separator arm 83 of the rocker passes up behind the front sheet or leaf or between the forwardly bowed front sheet and the next sheet so as to positively effect the required separation with the edge of the separated or front sheet or leaf in the plane of the space between the jaws 35^a which have been spread as above indicated. At this stage in the operation of the clutch of which one member has been moving idly by reason of the slot or cut away segment 54, communicates motion to the cam 41 to cause its cam face 48 to act on the lug 49 and thus pivotally raise the leaf

turning arm to bring its jaws 35^a into engagement with the separated leaf and withdraw said jaws from engagement with the spreader arm 82 of the rocker 81 so that said jaws 35^a snap together and clamp the leaf to the end that the swing movement of the leaf turning arm will cause it to carry with it the leaf until having approached the turned position when the leaf is released by the contact of one of the lugs 35^a with the stop pin 35^d.

In the construction illustrated the means for communicating motion from the slide bar to the rockers constituting the separators consist of travellers 87 secured to the slide bar and provided with runners 88 having looped intermediate portions extending around drums 89 attached to the spindles 84. The runners are provided as in the case of those used in the operating mechanism for the main spindle, with adjusting nuts 90 by which the tension thereof may be taken up as required.

The bearing shoes 85 which as above noted are carried by opposite ends of the slide bar 79 are carried by rockers 90' pivoted as at 91 to forwardly directed terminals of the slide bar, said rockers having tapered cam arms 93 for engagement with pins 94 which serve to control the positions of the shoes. In other words referring to the right hand shoe which comes into operation when the leaf is to be turned forward or in the direction of progressive performance, the movement of the slide bar in the opposite direction to that indicated by the arrow in Fig. 3 serves to bring the cam arm 93 into engagement with the pin 94 and withdraw the shoe from engagement with the leaf or sheet, whereas movement in the direction of the arrow as when a leaf is about to be turned, and when it is desired to utilize the effect of the shoe, will disengage the cam 93 from the pin 94 and permit the shoe to come into contact with the sheet or leaf through the action of a spring 95 or its equivalent located adjacent to the pivotal mounting of the shoe carrying rocker.

In view of the desirability of having the hand lever arranged with its finger pieces 115 as close to the finger board of the instrument as possible to minimize the distance required for movement of the hand with relation to the keyboard in operating the same, and at the same time in order to provide for supporting the apparatus so that closing of the roller board or keyboard cover of the instrument may not be prevented or interfered with, it is preferable to arrange the operating mechanism including the hand lever and rocker by which motion is communicated therefrom to the traveller in a pendent supplemental housing 96 pivotally mounted as by the thumb screws 97 to the main housing or base 20 which 130

locates the axis of said pendent frame in the horizontal plane of the shifter rod 65 upon which the hand lever is fulcrumed. The rocker 74 which has engagement as above

- 5 described with the traveller 58 by means of a pin 76 seated between the flanges 77 will therefore swing out of engagement as the said pendent frame is turned upward on the thumb screws 97 as an axis, and will 10 be restored to engagement when the pendent frame is returned to its normal position without special manipulation or adjustment. The shifter rod 65 is provided in axial alignment with the thumb screws 97 15 with a joint 98 thus permitting it to bend to accommodate the swinging movement of said supplemental pendent housing.

Having described the invention, what is claimed as new and useful is:—

- 20 1. A music leaf turner having a desk, a leaf turning arm mounted for swinging movement on the desk, a manually movable actuating member, a main spindle operatively connected with the actuating member and 25 having a lost motion connection with the turning arm, and means for moving said turning arm perpendicularly to its path of swinging movement during the interval of operation of the lost motion connection to 30 effect engagement of the arm with a leaf to be turned, said arm being provided with leaf engaging elements yieldingly impelled towards each other, and means for spreading said elements during the interval of 35 perpendicular movement of the arm.

2. A music leaf turner having a desk, a leaf turning arm mounted for swinging movement on the desk, a manually movable actuating member, a main spindle operatively 40 connected with the actuating member and having a lost motion connection with the turning arm, and means for moving said turning arm perpendicularly to its path of swinging movement during the interval of 45 operation of the lost motion connection to effect engagement of the arm with a leaf to be turned, said arm being provided with leaf engaging elements yieldingly impelled toward each other, and means for spreading 50 said elements during the interval of perpendicular movement of the arm, and a desk carried impact element for engagement with the arm to effect separation of the leaf engaging elements for the release of an inter- 55 posed leaf.

3. A music leaf turner having a desk, a leaf turning arm mounted for swinging movement, a manually movable actuating member, a main spindle operatively connected with the actuating member and having a lost motion connection with the turning arm, and means for moving the said arm perpendicularly to its path of swinging movement to effect engagement thereof with a 60 leaf to be turned, said leaf turning arm hav- 65

ing terminal yieldingly closed sheet engaging jaws, in combination with means actuatable by said spindle for spreading the jaws as they approach the leaf.

4. A music leaf turner having a desk, a leaf turning arm mounted for swinging movement, a manually movable actuating member, a main spindle operatively connected with the actuating member and having a lost motion connection with the turning arm, and means for moving the said arm perpendicularly to its path of swinging movement to effect engagement thereof with a leaf to be turned, said leaf turning arm having terminal yieldingly closed sheet engaging jaws, in combination with means actuatable by said spindle for spreading the jaws as they approach the leaf and including a rocker having a spreading arm to pass between the said jaws. 70 75 80

5. A music leaf turner having a desk, a leaf turning arm mounted for swinging movement, a manually movable actuating member, a main spindle operatively connected with the actuating member and having a lost motion connection with the turning arm, and means for moving the said arm perpendicularly to its path of swinging movement to effect engagement thereof with a leaf to be turned, said leaf turning arm having terminal yieldingly closed sheet engaging jaws, in combination with means actuatable by said spindle for spreading the jaws as they approach the leaf and including a rocker having a spreading arm to pass between the said jaws. 90 95 100

6. A music leaf turner having a desk, a leaf turning arm mounted for swinging movement, a manually movable actuating member, a main spindle operatively connected with the actuating member and having a lost motion connection with the turning arm, and means for moving the said arm perpendicularly to its path of swinging movement to effect engagement thereof with a leaf to be turned, said turning arm having terminal yieldingly closed sheet engaging jaws, in combination with a rocker having a jaw 105 spreading arm and a leaf separating arm, a leaf bowing device having a shoe movable toward the center of the desk, and connections between said rocker and shoe carrying means and said spindle. 110 115 120

7. A music leaf turner having a desk, a leaf turning arm mounted for swinging movement, a manually movable actuating member, a main spindle operatively connected with the actuating member and having a lost motion connection with the turning arm, and means for moving the said arm perpendicularly to its path of swinging movement to effect engagement thereof with a leaf to be turned, in combination with a 125 130

sheet bowing device consisting of a rocker having a frictional shoe for contact with the surface of a sheet, a trip pin in the path of a cam on said rocker for withdrawing the shoe from contact with the sheet, and a carrier for the rocker movable toward the center of the desk and operatively connected with said spindle.

8. A music leaf turner having a desk, a leaf turning arm mounted for swinging movement, a manually movable actuating member, a main spindle operatively connected with the actuating member and having a lost motion connection with the turning arm, and means for moving the said arm perpendicular to its path of swinging movement to effect engagement thereof with a leaf to be turned, the said operating connections including drums respectively carried by said spindle and connected with the means for effecting perpendicular movement of said arm, a traveller having runners respectively engaging said drums, and a rocker movable by said actuating member and operatively connected with the traveller.

9. A music leaf turner comprising a leaf turning arm mounted for swinging movement, a manually movable actuating member, a main spindle having a lost motion connection with the turning arm, a cam mounted to rotate in opposition to the spindle and impart perpendicular movement to the turning arm during the interval of operation of the lost motion connection and operative connections between the cam and manually actuating member and between the spindle and actuating member.

10. A music leaf turner comprising a leaf turning arm mounted for swinging movement, a manually movable actuating member, a main spindle having a lost motion connection with the turning arm, a cam mounted to rotate in opposition to the spindle and impart perpendicular movement to the turning arm during the interval of operation of the lost motion connection and operative connections between the cam and manually actuating member and between the spindle and actuating member, said connections including a selectively operable clutch between the actuating member and the cam.

11. A music leaf turner comprising a leaf turning arm mounted for swinging movement, a manually movable actuating member, a main spindle having a lost motion connection with the turning arm, a cam mounted to rotate in opposition to the spindle and impart perpendicular movement to the turning arm during the interval of operation of the lost motion connection and operative connections between the cam and manually actuating member and between the spindle and actuating member, and a depressible hand lever for imparting longitudinal movement to said manually actuatable member.

12. A music leaf turner comprising a leaf turning arm mounted for swinging movement, a manually movable actuating member, a main spindle having a lost motion connection with the turning arm, a cam mounted to rotate in opposition to the spindle and impart perpendicular movement to the turning arm during the interval of operation of the lost motion connection and operative connections between the cam and manually actuating member and between the spindle and actuating member, said connections including a selectively operable clutch between the actuating member and the cam, and a depressible hand lever for imparting longitudinal movement to said manually actuatable member and provided with an auxiliary lever for the selective operation of said clutch.

13. A music leaf turner having a leaf turning arm mounted for swinging movement, a manually actuating member operatively connected with the leaf turning arm, said leaf turning arm having transverse yieldingly closed sheet engaged jaws, a spreading arm operatively connected with the manually actuating member and disposed to separate the jaws of the leaf turning arm to permit leaf engaging operation thereof.

14. A music leaf turner having a leaf turning arm mounted for swinging movement, a manually actuating member operatively connected with the leaf turning arm, said leaf turning arm having transverse yieldingly closed sheet engaged jaws, a spreading arm operatively connected with the manually actuating member and disposed to separate the jaws of the leaf turning arm to permit leaf engaging operation thereof, said leaf turning arm being provided with depending stop lugs arranged in transverse alignment, and stop pins for impact with said lugs to separate the leaf engaging jaws to permit leaf releasing movement thereof.

15. A music leaf turner having a desk, a leaf turning arm mounted for swinging movement on the desk, an actuating member moved longitudinally of the desk, a main spindle operatively connected with the actuating member and having a lost motion connection with the turning arm, a supplemental pendent housing having a hinged connection with the desk, and an actuating lever carried in said housing and operatively connected with the actuating member.

16. A music leaf turner having a desk, a leaf turning arm mounted for swinging movement on the desk, an actuating member longitudinally movable of the desk, a main spindle operatively connected with the actuating member and having a lost motion connection with the turning arm, means for moving the turning arm perpendicular to its

- path of swinging movement to effect engagement thereof with a leaf to be turned, clutch controlled connections between said means and said actuating member, a supplemental pendent housing foldably connected with the desk, a depressible hand lever carried in said housing and operatively connected with the actuating member, and an auxiliary lever carried by the actuating lever and operatively connected with said clutch controlled connection.
- In testimony whereof he affixes his signature.
- JAMES J. THOMPSON.
